JET TYPE BAILER WITH GAS GENERATING MECHANISM

Vaughn D. Hanes, West Covina, Calif., assignor to Aerojet-General Corporation, Azusa, Calif., a corporation of Ohio

Application June 1, 1956, Serial No. 588,827

6 Claims. (Cl. 166—63)

This invention relates to oil well tools, and in particular, to a bailer for removing debris or other materials from a well bore.

An object of the invention is to provide a bailer with a powerful, self-contained jetting means which is not dependent upon high submergence pressures for efficient operation.

Another object is to provide a jet type bailer in which it is not necessary to lift debris the entire height of the bailer in order to fill the bailer.

Another object is to provide a bailer from which the debris contained therein can be easily removed.

Another object is to provide a jet type bailer which can be run on a conventional steel line without the use of an insulated electric cable.

This invention includes a bailer body having upper and lower compartments, one compartment comprising a gas generating chamber and the other compartment or compartments being so disposed and arranged as to receive debris which has been elevated above the lower end of the bailer by the jet stream issuing from a nozzle connected to the gas generating chamber.

Bailers or sand pumps for the removal of debris from wells require a high fluid head in order to operate efficiently. Propellant jet type bailers, on the other hand, operate most efficiently under low fluid heads. This is because low fluid heads create less back pressure on the propellant combustion chamber and therefore permit a slower burning rate and an increased volume of gas production.

A problem in the design of propellant jet type bailers is the positioning of the propellant combustion chamber with respect to the bailer compartment. If the propellant chamber is located below the bailer compartment (in order to employ an ignition system which is actuated upon striking a bridge or the bottom of the well) the debris must be raised to a considerable height, on the order of 40 to 60 feet, in order to permit the debris to enter the top of the bailer compartment. This necessitates the use of an excessive amount of propellant. An important object of the present invention is to provide a bailer compartment so arranged as to fill, or substantially fill, the bailer.

The foregoing and other objects and advantages of the invention will be evident from the following description and drawings wherein:

Fig. 1 is an elevation showing a bailer completely assembled in a well;

Fig. 2 is an elevation, in cross section, of the upper portion of a bailer;

Fig. 3 is an elevation, in cross section, of the lower or combustion ignition chamber portion of the device shown in Fig. 2;

Fig. 4 illustrates an alternate type of jet nozzle for use with the invention; and

Fig. 5 illustrates another embodiment of the invention

wherein the buckets are flexible and the gas generating chamber is located above the buckets.

The general arrangement of the major parts of the bailer is best illustrated in Fig. 1. The bailer is shown suspended in a well casing 1 by means of a wire line 2 and a conventional socket connector 3. The outer surface of the bailer is spaced from the wall of the bore at all times. The bailer may have one or more debris buckets 4 secured together in end-to-end relation, several such buckets being illustrated. Attached to the lowermost bucket is a propellant chamber 5, below which is an ignition assembly 6 having a downwardly directed nozzle 7. The nozzle 7 is shown suspended slightly above the top of a bridge formed by a body of debris 8 in the well casing 1. A fluid jet issuing from the nozzle 7 blasts the debris 8 upwardly through the well fluid 9 in the direction of the arrows 10 and into the interiors of the buckets 4, as the latter are hoisted from the well, as will be explained more fully.

Referring to Fig. 2, the upper end of the uppermost bucket 4 is provided with a typical cable tool pin joint as shown at 11, adapted to be threaded attached to the socket 3 (Fig. 1) supported by the wire line 2. The lower end of the pin joint 11 is attached to the upper end of the bucket 4 by suitable means, such as the threads 12. The pin joint 11 may or may not be provided with a number of inlet holes 13 to enable debris that may tend to accumulate on the shoulder of the joint to enter the bucket 4 suspended from the joint.

The buckets 4 are tubular in form with fluid inlets 14 at their upper ends and closures 15 at their lower ends. The buckets 4 may be provided with drain ports 16 in their walls to permit well fluid to drain back into the well while retaining solid debris.

The buckets 4 are connected together by any suitable means such as the coupling 17 which are threaded attached to adjacent buckets by the threads 18. The couplings 17 may be provided with closure partitions 15 for the lower ends of the buckets 4.

In the event that the debris to be removed from the well contains a substantial amount of fine, flour-like sand which would pass readily through the drain ports 16, tubular screen liners 19 may be inserted in each of the buckets 4 to strain the sand out of the well liquids.

The mesh of the screens 19 can be varied to suit the sand conditions encountered in different wells. The screen liners 19 may be provided with vertical stiffener rods 20 attached to rings 21—22 at opposite ends of the tubular screens. The lower ring 22 may be provided with handle 23 for convenience in assembly or removal. A retainer pin 24 may be positioned within the bucket 4 above the top ring 21 to prevent upward movement of the tubular screen 19. The lower end of the screen 19 is supported by a coupling member 17 or 25.

The propellant chamber 5 is attached to the lower end of the lowermost bucket 4 by any suitable means such as the tubular coupling 25 which is threaded at both ends as indicated at 26 and provided with an O ring seal 27 between the walls of the coupling 25 and the propellant chamber 5. The tubular coupling 25 is provided with a closure member 28. Depending from the closure member 28 is a helical compression spring 29 secured to the closure member by any suitable means such as a bolt 30. The lower end of spring 29 bears against the upper end of a grain 31 of solid propellant to keep the grain from loose movement and possible breakage during handling and shipping.

Referring to Fig. 3, the lower end of the propellant grain 31 is supported on a spider 32 having passageways 33 therethrough for the passage of gas generated by the burning of the propellant 31.

The spider 32 may be provided with a central opening 34 adapted to receive a percussion cap 35 which is held in place by means of a threaded bushing 36. The lower end of the propellant grain 31 is shown as being recessed at 37 to receive the percussion cap 35, although such a construction is not essential.

The spider 32 is supported on the upper end of a tubular housing 38 by suitable means such as the threaded connection 39. The tubular housing 38 is supported at its lower end on the tubular housing 6 by any suitable means such as the threaded connection 40. The housing 38 is provided with passageways 41 and 42 which permit gas from the propellant chamber to pass therethrough. The upper end of the tubular housing 6 is attached to the lower end of the propellant chamber 5 by any suitable means such as the threaded connection 43. An O ring 44 provides a seal between the walls of the housing 6 and the propellant chamber 5.

The upper end of the nozzle 7 extends within the lower end of housing 6 and terminates in an enlarged upper end 45 having a downwardly facing shoulder 46. A bushing 47 is threadedly connected to the lower end of housing 6, as indicated at 48. The upper end of bushing 47 bears against the downwardly facing shoulder 46 on the head 45 and prevents the nozzle 7 from dropping out of the housing 6.

The nozzle 7 is slidable axially and telescopically within the housing 6 and is yieldably held in its extended position by a coil compression spring 49 mounted in a cylindrical chamber 50 within the housing 6. The spring 49 is confined, in a compressed condition, between a downwardly facing shoulder 51 in housing 6 and an upwardly facing shoulder 52 on the upper end of nozzle 7. Spacer washers 53 may be inserted between the spring 49 and nozzle 7 to adjust the spring compression if desired.

The upper end of the nozzle is provided with an upwardly extending tubular extension 54 of reduced diameter and which passes slidably through an opening 55 in the upper end of housing 6. An O ring 56 provides a sliding seal between the nozzle extension 54 and the opening 55. The upper end of the tubular extension 54 is provided with an enlarged chamber 57, threaded internally as indicated at 58, to receive a threaded valve cage 59. An O ring 60 seals the walls between the valve cage 59 and the enlarged chamber 57. The upper end of valve cage 59 is normally closed by a cover plate 61 having an upwardly extending boss 62. The boss 62 is threaded externally as indicated at 63 and is provided with a vertically extending bore 64. Within the bore 64 there is mounted a pressure-responsive closure valve 65. Valve 65 has an enlarged head 66 on the lower end thereof to prevent upward movement of the cylindrical valve shank 67 through the bore 64 in cover plate 61. The shank is provided with an external groove 68 in which there is positioned an O ring 69 which forms a slidable seal between the shank 67 and bore 64. The upper end of shank 67 extends beyond the top of the boss 62 and engages a frangible keeper 70 which normally prevents the valve 65 from moving downwardly out of the bore 64. The valve 65 is effective to prevent well fluid from passing upwardly into the passages leading from the nozzle 7 to the propellant chamber until the valve is opened, but not removed from the passageway, by gas pressure generated by burning of the propellant.

Threadedly connected to the boss 62 is an upwardly extending tubular sleeve 71 which contains the striker mechanism for initiating the percussion cap 35. Intermediate to the ends of the sleeve 71 is a barrier wall 73 separating the interior of the sleeve 71 into upper and lower chambers. The lower chamber is provided with ports 72 in the walls thereof. The upper chamber is provided with a spring-actuated firing pin 74. Preferably, the firing pin 74 is cylindrical in shape with a solid

upper portion having a downwardly depending skirt 75 within which is confined a compression spring 76 supported by the barrier wall 73. The spring 76 is normally held in compressed position by means of a ball 5 detent 77 mounted in an aperture 78 in the wall of the sleeve 71 in the upper chamber thereof. The firing pin 74 is provided with a circumferential boss 79 on the outer surface thereof which normally engages the underside of the ball 77. The ball 77 is normally constrained 10 against outward movement by contact with the inner surface of the tubular housing 38. The upper interior surface of the tubular housing 38 is recessed as indicated at 80 to permit the ball detent 77 to disengage the boss 79 upon upward movement of the sleeve 71 with respect 15 to the housing 38. This disengagement occurs when the sleeve 71 moves upward to the position indicated in dotted lines 81. Thus released, the firing pin moves rapidly upward, urged by the spring 76 until it strikes the percussion cap 35, thus initiating detonation of the 20 cap, which, in turn, ignites the propellant 31.

Upward movement of the nozzle 7 and the associated firing mechanism is initiated by contact of the lower end of nozzle 7 with top of a bridge or debris 8 (Fig. 1) in the well. The amount of upward movement of the 25 nozzle 7 with respect to the ignition chamber 6 is limited by the distance between the head 45 on the nozzle 7 and a downwardly facing shoulder 82 on the interior of the chamber 50 in the housing 6. The wall of chamber 50 is provided with ports 83 to permit well fluid to enter 30 or leave the chamber 50.

The interior lower end of nozzle 7 is preferably provided with a replaceable orifice bushing 84 threadedly secured within the nozzle 7 as indicated at 85.

The exterior lower end of nozzle 7 is preferably threaded as indicated at 86 to receive tubular foot pieces 87 or 88 (in dotted lines) of different diameters, depending upon the degree of solidity of the debris in the well. Loose debris may require a larger area of footing in order to insure that the nozzle 7 will be moved upwardly upon contact with the debris. The spring 49 should be strong enough to prevent accidental upward movement of the nozzle 7 while the tool is being run into the well. A shear pin, not shown, could be inserted between the nozzle 7 and housing 6 to prevent premature upward movement of the nozzle 7.

Fig. 4 illustrates a modification of the nozzle portion of the bailer shown in Fig. 3. The lower end of the ignition chamber is indicated at 6a and 47a, and is similar to the chamber 6 and 47 of Fig. 3. The nozzle 7a differs from the nozzle 7 in that it is tapered downwardly and inwardly, as indicated at 89 and terminates in relatively sharp point 90, the more easily to penetrate into the body of debris 8 (Fig. 1). The lower end 91 of the nozzle 7a may be a separate, detachable piece, threadedly connected to the nozzle 7a as indicated at 92. The nozzle 7a is provided with a fluid passageway 54a which communicates with a similar passageway 54b in the nozzle tip 91. Adjacent the lower end of passageway 54b there are two or more upwardly directed jet passageways 93. In operation, when the nozzle end 91 is embedded 60 in the debris 8, fluid jets issuing from the jet passageways 93 will not only dislodge the debris by developing a fluid pressure below the surface of the debris but will also move the loosened debris upwardly toward the buckets 4.

The buckets 4 shown in Figs. 1 and 2 are rigid, metal buckets of smaller diameter than the well casing 1 through which they must pass freely, allowing ample clearance between the walls of the buckets and the internal walls of the casing 1. Close clearances between the buckets 4 and casing 1 not only slow down the running in of the bailer but also tend to cause the bailer to become stuck in the casing when debris becomes lodged between the buckets and the casing. It is not essential 70 to the present invention that the buckets 4 be rigid or

not raise the debris to a point above the top of the bailer body.

The foregoing description and drawings are illustrative only. The present invention is not to be limited thereto, but is of the scope defined by the appended claims.

I claim:

1. A cable suspended well bailer adapted for use in a well casing comprising: an elongated body having a chamber therein, said body adapted to be spaced clear of the well casing, means for gas generation arranged within said chamber, a downwardly directed nozzle arranged at the lower end of said body, conduit means for leading gas from said chamber to said nozzle, and a plurality of debris collecting means having greater volume than the gas generating chamber, said debris collecting means being attached to said elongated body and provided with lateral openings intermediate the length thereof, whereby an unobstructed path is provided for the upward flow of debris dislodged from the bottom of the well, said debris being lodged in the debris collecting means by passage through said large lateral openings thereof and retention therein.

2. A well bailer as described in claim 1 in which telescopic mounting means is arranged on said body for said downwardly directed nozzle, a first resilient means for normally holding said nozzle in an extended position, a firing pin projectably mounted on the inner end of said nozzle, means actuated by said firing pin to initiate operation of the gas generating means, and means effective to retain said firing pin in retracted position on said nozzle until such time as said nozzle has been composed of metal. For example, the buckets could be formed of flexible material, such as rubber, as shown in Fig. 5.

Fig. 5 illustrates schematically an embodiment of the invention wherein flexible buckets or cups 94 are employed in place of the rigid metal buckets 4. The flexible cups are of lesser diameter than the well casing 1a and are mounted one above the other, with their open ends facing upwardly, on a pipe 95 which provides a fluid passageway from a propellant chamber 96 to a jet nozzle 97. The bailer is suspended from a hoisting line 2a which may be either a stranded steel cable or an insulated electric conductor cable.

The operation of the bailers shown in the drawings is obvious from the foregoing description of several embodiments of the invention. When the bailer is in position on top of the debris in the well, the propellant is ignited. High pressure gas is generated in the propellant chamber and discharged downwardly through the jet nozzles. Loosened debris is forced upwardly above one or more of the buckets. The bailer is then pulled upwardly by means of the supporting cable. As the bailer moves upwardly, debris is deposited in the buckets while well liquids are strained out through the drain ports (if such drain ports are employed). The use of a series of vertically spaced buckets, instead of one, long (40 to 60 foot) pipe, open at its upper end, will insure that some, if not all, of the debris raised by the jet, will enter one or more of the buckets even though the jet might

urged inwardly toward said body a predetermined distance by engagement with the bottom of the well.

3. A well bailer as defined in claim 2 in which second resilient means is mounted to project said firing pin, and detent means holding said second resilient means in compressed condition until such time as said nozzle has been urged inwardly toward said body a predetermined distance by engagement with the bottom of the well.

4. A bailer adapted for operation in a well casing comprising: an elongated body having a chamber therein, said body adapted to be spaced clear of the well casing, means for generating gaseous pressure arranged within said chamber, nozzle means arranged at the lower end of said body, the lower end of said nozzle means being tapered downwardly and inwardly to terminate in a point, conduit means for leading gas from said chamber to said nozzle means, said nozzle means having upwardly and outwardly directed fluid jet passageways therein arranged above the lower end thereof, said passageways communicating with said conduit means, the lower end of said nozzle means being formed as a solid member adapted to penetrate into and be arrested by debris at the bottom of said well, and debris collecting means attached to said elongated body, whereby an unobstructed path is provided for the upward flow of debris dislodged from the bottom of the well, and lodgment thereof in the debris collecting means.

5. A well bailer as defined in claim 1 wherein said conduit means comprise a passageway, and valve means mounted in said passageway whereby said valve means normally close said passageway to prevent the entry of well fluid thereto but are opened to permit the flow of pressurized gas through said passageway when the generated gas pressure exceeds a predetermined value.

6. A well bailer as described in claim 1 wherein said debris collecting means comprise a plurality of vertically spaced buckets connected between the chamber containing body and the suspending cable, said buckets having lateral openings at their upper end, cable attaching means carried at the upper end of the uppermost bucket, tubular couplings having closure partitions therein connecting the buckets in superposed relation to one another and the lowermost bucket to the upper end of said chamber body to provide a rigid bailer structure.
